UNITED STATES PATENT OFFICE.

ANNA E. SIMPSON, OF CORONA, TERRITORY OF NEW MEXICO.

CUSPIDOR.

No. 884,871.

Specification of Letters Patent.

Patented April 14, 1908.

Application filed June 20, 1907. Serial No. 379,954.

To all whom it may concern:

Be it known that I, ANNA E. SIMPSON, a citizen of the United States, residing at Corona, in the county of Lincoln, Territory of New Mexico, have invented certain new and useful Improvements in Cuspidors; and I do hereby declare the following to be a full, clear, and exact description of the invention, such as will enable others skilled in the art 10 to which it appertains to make and use the same.

This invention relates to new and useful improvements in cuspidors, and it pertains particularly to a cuspidor of that type which 15 includes hinged or collapsible sections and which is employed in connection with a flexible moisture proof bag.

The invention aims as a primary object to provide a cuspidor of this class which shall be neat in its appearance, and in which the joints between the several parts are practically sealed.

The invention aims as a further object to provide a novel construction, combination and arrangement of parts, the details of which will appear in the course of the following description, in which reference is had to the accompanying drawings forming a part of this specification, like characters of 25 reference designating similar parts throughout the several views, wherein:

Figure 1 is a side elevation of a cuspidor constructed in accordance with the present invention, the parts being assembled for use. 30 Fig. 2 is a similar view with the parts disengaged. Fig. 3 is a top plan view. Fig. 4 is an enlarged sectional view illustrating the manner of engaging the overlapping edges of the hinged sections with the bowl of the cuspidor. Fig. 5 is a detailed view of the removable moisture proof bag above referred to, such bag being preferably constructed of oiled paper.

Referring specifically to the accompanying drawings, the numeral 6 designates the bowl of the cuspidor which, along its upper edge is constructed with an annular bead 6'. Hingedly connected to the bowl 6, at diametrically opposite points, are the cover sections 7 and 8. These sections are counterparts in construction, and the hinged joints designated by the numeral 9 are located centrally there-

of. The sections 7 and 8 complement one another to form a complete cover and are constructed with enlarged semi-dished shaped 55 base portions 10, centrally located semi-anularly neck portions 11, and semi cone shaped upper portions 12, which together form the flaring mouth of the cuspidor. At their lower ends, said sections have beads 7' 60 and 8' stamped thereinto which interfit in the bead 6' so as to effect a substantial sealed joint with the bowl 6 and so as to strengthen the parts in their hinged relation. Each of said sections 7 and 8, carry at their upper 65 portions and at opposite sides suitable catches 13, which are formed for engagement with the keepers 14 provided upon the adjacent side of the opposing section. Disposed in the bowl 6 is the oil paper bag 15, illustrated more particularly in Fig. 5 and constructed with a reduced crimped neck 16, which is designed to interfit the neck of the cuspidor afforded by the portions 11 in their confronting relation.

The mouth of the bag overlies the mouth of the cuspidor so as to protect the same. Said bag may be conveniently removed by disengaging the catches 13 from the keepers 14, and by swinging the sections 7 and 8 to 70 the position of Fig. 2.

The invention is simple in its structural details, inexpensive to manufacture and practical and efficient in use.

What is claimed is:

In a cuspidor, the combination of a bowl-like base having an annular bead adjacent its free edge, cover sections hinged to the base at opposed points, said cover section having beads formed around the lower free edges, 90 the beads of the cover sections fitting within the bead of the base when in closed position, means carried by the cover sections for holding said cover sections in closed position and an impervious flexible receptacle fitting with 95 in the base and inclosed by the cover sections when said cover sections are in closed position.

In testimony whereof, I affix my signature, in presence of two witnesses.

ANNA E. SIMPSON.

Witnesses:

E. M. DU BOIS,
E. G. PALMER.
